UNITED STATES PATENT OFFICE.

DANIEL L. REBER, OF AMANDA, OHIO, ASSIGNOR OF ONE-HALF TO WILLIAM BORCHERS, OF SAME PLACE.

SASH-CORD FASTENER.

SPECIFICATION forming part of Letters Patent No. 425,906, dated April 15, 1890.

Application filed January 23, 1889. Renewed December 30, 1889. Serial No. 335,324. (No model.)

To all whom it may concern:

Be it known that I, DANIEL L. REBER, a citizen of the United States, and a resident of Amanda, in the county of Fairfield and State 5 of Ohio, have invented certain new and useful Improvements in Sash-Cord Fasteners; and I do hereby declare that the following is a full, clear, and exact description of the invention, which will enable others skilled in the art to 10 o which it appertains to make and use the same, reference being had to the accompanying drawings, which form a part of this specification, and in which—

Figure 1 is a perspective view of a portion 15 of a window-sash provided with my improved cord lock or fastener. Fig. 2 is a side view of part of one of the stiles with the sash-cord and fastener in position. Fig. 3 is a similar view showing the sash-cord removed. Fig. 20 4 is a perspective view of one end of the sash-cord with its interlocking disk and its shank. Fig. 5 is a perspective detail view of the fastening or interlocking thimble removed from the sash-stile. Fig. 6 is a cross-section on 25 line $x-x$ in Fig. 2, and Fig. 7 is a longitudinal sectional view on line $y-y$ in Fig. 2.

Like letters of reference denote corresponding parts in all the figures.

This invention has relation to devices for 30 fastening the inner ends of counterpoised sash-cords in the stiles of sliding window-sashes, and has for its object not only to make such fastening strong, durable, and secure, but also to permit of the instantaneous fastening or unfastening of the cord when, for example, the sash is to be removed for repair or for other reasons.

To this end my invention consists in the combination, with a sliding sash, of the improved 35 cord-lock or fastening device, which will be hereinafter more fully described and claimed.

Reference being had to the accompanying drawings, the letter A denotes one of the stiles 40 of a sliding window-sash, B one of the sash-cords or counterpoise-cords, and C the usual groove or recess for the reception of the latter. At the point where the cord is to be fastened to the sash a hole D is bored through the 45 stile at right angles to and intersecting the

groove C, and into this hole or aperture is fitted a cylindrical thimble E, which may be of cast-iron or any other suitable material, closed at one end by an end piece or plate F, which is flush with the face of the stile. The 55 end plate F, together with the upper corner of the cylindrical body of the thimble, is cut away to form a slot or opening G, having an enlargement H in the center of plate F. The slot G H is of such dimensions that it will receive the disk I of the sash-cord when inserted endwise, said disk being integral with the stem or shank J, which is fastened permanently upon the sash-cord by means of the clamping-sleeve K and rivets L. 60

From the foregoing description, taken in connection with the drawings, the manner of using this device will readily be understood. The cord is fastened in the stile by inserting disk I edgewise and endwise into the narrow 65 slot or aperture G in the end of the thimble, and by then giving shank J a quarter-turn in the central enlargement H and turning it with its sleeve K and the sash-cord B up into the groove it will firmly interlock with the 70 thimble without a possibility of its becoming accidentally detached after the sash has been placed in its frame or casing. After the sash has been removed, however, the cord may be instantly detached simply by reversing the 75 80 operation whereby it is fastened in the sash.

I am aware that a sash-cord fastener consisting of a cylindrical open sleeve provided with a slot in one end to receive the end of the sash-cord has been provided, and also 85 that a plate having a chamber formed thereon provided with an angular slot to receive a shank having a disk is not new, and such constructions I do not claim; but what I claim is a cylindrical thimble having a closed end, 90 an angular slot in said end, and a hollow tubular shank having a disk adapted to interlock with said slot.

The advantages of my device are: The closed end prevents the disk from contacting with 95 the window-frame, which would cause the sash to wedge therein, and also retain the disk in place at all times, and a further advantage is the forming of the shank hollow, whereby it will receive and retain the cord therein. 100

Having thus described my invention, I claim and desire to secure by Letters Patent of the United States—

The combination, with the sash having the 5 groove or channel communicating with the cylindrical socket, of the ferrule or sleeve fitting in said socket, having its outer end closed, arranged in line with the sash, and formed with a right-angled slot, and the hollow shank 10 having one end interlocking with the ferrule

and the other end arranged in the groove of the sash and receiving the sash-cord, substantially as shown, and for the purpose described.

In testimony that I claim the foregoing as my own I have hereunto affixed my signature 15 in presence of two witnesses.

DANIEL L. REBER.

Witnesses:

CHARLES H. SUNDERMAN,
WILLIAM BORCHERS.
